CLOTH UNWINDER

Maximilian Breth, Ozone Park, N. Y.

Application October 22, 1937, Serial No. 170,369

14 Claims. (Cl. 242—68)

This invention relates to cloth unwinders.

An object of this invention is to provide a cloth unwinder in which a roll or bolt of cloth rests on a plurality of parallel rollers during the unwinding operation, thus eliminating necessity for core support.

A further object of this invention is to provide a cloth unwinder of the character described, on which there may be unwound a roll of cloth which is wider than the table on which the unwinder is supported, and in which there is provided adjustable end stops to accommodate rolls or bolts of cloth of various width.

Still another object of this invention is to provide a cloth unwinder of the character described which is collapsible and in which projecting parts may be removed for packing and shipping the machine in compact form.

Another object of this invention is to provide a compact, strong and rugged machine of the character described which shall be relatively inexpensive to manufacture, on which cloth may be very easily unwound, and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is an end view of a cloth unwinder with a roll of cloth thereon in position for unwinding the cloth from the roll;

Fig. 2 is a front elevational view of the structure shown in Fig. 1, with parts in cross section;

Fig. 3 is an enlarged cross-sectional view taken on line 3—3 of Fig. 2;

Fig. 4 is a side elevational view of the screw thread extension bar;

Fig. 5 is an elevational cross-sectional view of an extension bar, illustrating a modified construction, and

Fig. 6 is a cross-sectional view taken on line 6—6 of Fig. 5.

Referring now in detail to the drawing, 10 designates a cloth unwinder embodying the invention, and 11 designates a roll of cloth mounted on said unwinder and showing the cloth 12 from the roll being unwound therefrom. The unwinder 10, comprises a pair of similar parallel vertical side frames or stanchions 14.

Each frame 14 has an upwardly and rearwardly inclined straight portion 15 from which there extends a downwardly and forwardly curved portion 16. Extending from the bottom end of said

straight portion 15, is a downwardly and rearwardly inclined leg 17, which may carry a rubber shoe 18 to contact the top of the table 19.

Extending downwardly from the front end of the curved portion 16 is an ear 20, and extending from said ear, is a forwardly and upwardly curved portion 21 having substantially the same curvature as said portion 16. Extending from said portion 21 of the frame 14 is a downwardly and forwardly inclined leg 22, carrying a rubber shoe 23, engaging the table 19. The portions 20 of the side frames 14 are interconnected by a horizontal connecting bolt 25. The upper ends of the portions 15 of said side frames are also interconnected by a horizontal rod 26. The upper ends of curved portion 21 are also interconnected by a horizontal rod 27. The frames 14 are thus rigidly held together in vertical planes, by the members 25, 26 and 27.

The curved portions 16 and 21 of the frames 14 are provided with pairs of aligned bosses 28, formed with screw threaded through openings carrying threaded pins 29, having conical inner ends 30. On each pair of pins 29 there is rotatably supported a roller 31, comprising a sleeve 32 within the outer ends of which are fixed plugs 34, formed with central openings 35, receiving the conical portions 30 of said pins. The two rollers 31 are parallel and spaced from one another and are at the same height. The plugs 34 are made of metal so that the rollers may easily rotate on the conical ends 30. Lock nuts 37 are provided on said pins to hold the same in adjusted positions.

The roll of cloth 11 is placed on the roller 31, 35 the cloth 11 passing upwardly from said roll over the rod 26. Upon pulling the cloth 12, the roll 11 will turn easily on the rolls 31 to permit unwinding of the cloth.

Screwed within the ends of the rod 26 are extension bars 40 to be used when unwinding rolls of greater width than the width of the bar 26.

Adjustable stop means is furthermore provided for the ends of the roll of cloth 11. To this end the ears 20 of the frames 14 are formed with through openings 42. Slidably mounted within each opening 42 is a horizontal rod 43, formed at its outer end with an upwardly extending portion 44, terminating at the top in a circular portion 46. Slidably mounted on the rod 25 are a pair of circular disks 47, each formed with a through opening 48, through which said rod passes. The disks 47 are also formed with through openings 50, parallel to the openings 48, receiving the inner ends 52 of the rods 43. Said ends 52 of the rods 43 may be fixed to said disks 47 by tapered cotter pins 53, or in any other suitable manner. The disks 47 may also be provided with set-screws 55, adapted to engage the rod 25 for holding said disks in adjusted position on said rod.

By loosening the set-screws 55 the rods 43 may be moved in or out to accommodate rolls or bolts of cloth of various width. The portions 44, 46 of the rods 43 are adapted to act as stop means to prevent side movement of the roll 11. It will be noted that with my improved machine rolls of cloth may be unwound which are wider than the table 19. When shipping the machine the rods 43 are pushed inwardly toward each other and the extension rods 40 may be unscrewed. The unwinder may thus be shipped or stored in compact form.

As illustrated in Figs. 5 and 6 of the drawing, the rod 26 may be replaced by a tubular rod 26a and the extension bars 40 may be replaced by tubular bars 40a, telescoping within tube 26a. The tube 26a may be formed with elongated slots 60 and telescoping tubes 40a provided with lugs 61, disposed within the slots and adapted to engage the portions 15 of the frame to limit outward movement of said telescope tube. For the purpose of packing or shipping, the tube 40a need merely be pushed inwardly within the tube 26a so as not to project therefrom. It will be noted that with my improved unwinding machine, no centering cores are necessary to support the roll or bolt of cloth.

While the drawing illustrates the unwinding device used for unwinding cloth from a roll of cloth, it will be understood that other bolts of cloth may be unwound on said device, for example, bolts in which the cloth is rolled on flat boards.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. An unwinder for a roll of flexible sheet material, comprising a support, a pair of parallel, horizontal, aligned rollers on said support, and extensible means on said support serving as stops for the ends of a roll supported by said rollers, a horizontal rod on said support and above the level of said rollers, said rod having extensions beyond said rollers on both sides.

2. A cloth unwinder comprising a pair of similar, parallel supports disposed in vertical planes, each having an upwardly and rearwardly inclined arm, a horizontal rod interconnecting the upper ends of said inclined arms, a pair of parallel, horizontal rollers on said supports and below said arms and adapted to carry a roll of cloth to be unwound, and a pair of extensible members slidably connected to said supports for outward movement in opposite directions and having portions disposed in vertical planes to serve as stops for the ends of the roll, and extensions on said horizontal rod extending beyond said rollers on opposite sides.

3. A device for unwinding a roll of flexible sheet material, comprising a pair of parallel supports disposed in vertical planes, a pair of spaced, horizontal rollers on said supports, a horizontal bar parallel to said rollers and interconnecting said supports, a member slidably mounted on said bar, a second member having a horizontal

portion parallel to said bar and slidably mounted on one of said supports and connected to said first member, said second member having a vertical portion adapted to serve as an end stop for a roll supported on said horizontal rollers.

4. A device for unwinding a roll of flexible sheet material, comprising a pair of parallel supports disposed in vertical planes, a pair of spaced, horizontal rollers on said supports, a horizontal bar parallel to said rollers and interconnecting said supports, a member slidably mounted on said bar, a second member having a horizontal portion parallel to said bar and slidably mounted on one of said supports and connected to said first member, said second member having a vertical portion adapted to serve as an end stop for a roll supported on said horizontal rollers, a second horizontal bar interconnecting said supports and disposed above said horizontal rollers, and a pair of longitudinal extensions at the end of said last mentioned bar.

5. An unwinder for a roll of flexible sheet material, comprising a pair of spaced, parallel supports disposed in vertical planes, each support comprising an upwardly and rearwardly inclined arm, a downwardly and rearwardly inclined leg extending from said arm, a forwardly and downwardly curved portion extending from the bottom end of said arm, an upwardly and forwardly curved portion extending from said first curved portion, a forwardly and downwardly inclined leg extending from said upwardly curved portion, a horizontal rod interconnecting the upper ends of said upwardly and rearwardly inclined arms, a horizontal member interconnecting the upper ends of said upwardly and forwardly curved portions, and disposed at a lower level than said rod, another rod interconnecting said supports and disposed between said curved portions and at a lower level than said horizontal member, and a pair of horizontal, parallel rollers supported on and between said supports and disposed between said leg portions, and at a lower level than said horizontal member.

6. An unwinder for a roll of flexible sheet material, comprising a pair of spaced, parallel supports disposed in vertical planes, each support comprising an upwardly and rearwardly inclined arm, a downwardly and rearwardly inclined leg extending from said arm, a forwardly and downwardly curved portion extending from the bottom end of said arm, an upwardly and forwardly curved portion extending from said first curved portion, a forwardly and downwardly inclined leg extending from said upwardly curved portion, a rod interconnecting the upper ends of said upwardly and forwardly curved portions, a rod interconnecting said supports and disposed between said curved portions, and a pair of horizontal, parallel, aligned rollers supported on and between said supports and disposed between said leg portions, a pair of members slidably mounted on said last mentioned rod, a second pair of members having horizontal portions slidably mounted on said supports and connected to said first pair of members, said second pair of members having upwardly extending vertical portions adapted to engage the ends of a roll supported on said horizontal rollers.

7. An unwinder for a roll of flexible sheet material, comprising a pair of spaced supports disposed in vertical planes, each support comprising an upwardly and rearwardly inclined arm, a downwardly and rearwardly inclined leg extending from the bottom end of said arm, a forwardly

- and downwardly curved portion extending from the bottom end of said arm, an upwardly and forwardly curved portion extending from said first curved portion, a forwardly and downwardly 5 inclined leg extending from said upwardly curved portion, a rod interconnecting the upper ends of said upwardly and rearwardly inclined arms, a rod interconnecting the upper ends of said upwardly and forwardly curved portions, a rod interconnecting said supports and disposed between 10 said curved portions, a pair of horizontal, parallel, aligned rollers supported on and between said supports and disposed between said leg portions, and a pair of extensions on the outer ends of said 15 first rod.
8. An unwinder for a roll of flexible sheet material, comprising a pair of spaced, parallel supports disposed in vertical planes, each support comprising an upwardly and rearwardly inclined 20 arm, a downwardly and rearwardly inclined leg extending from said arm, a forwardly and downwardly curved portion extending from the bottom end of said arm, an upwardly and forwardly curved portion extending from said first curved 25 portion, a forwardly and downwardly inclined leg extending from said upwardly curved portion, a rod interconnecting the upper ends of said upwardly and rearwardly inclined arms, a rod interconnecting the upper ends of said upwardly and 30 forwardly curved portion, a rod interconnecting said supports and disposed between said curved portions, and a pair of horizontal, parallel, aligned rollers supported on and between said supports and disposed between said leg portions, a pair 35 of members slidably mounted on said last mentioned rod, a second pair of members having horizontal portions slidably mounted on said supports and connected to said first pair of members, said second pair of members having upwardly extending vertical portions adapted to engage the ends of a roll supported on said horizontal rollers, and a pair of extensions on the outer ends of said first rod.
9. An unwinder for a bolt of cloth comprising 40 a pair of parallel supports disposed in vertical planes, a pair of spaced, horizontal rollers mounted on and between said supports, to support a bolt of cloth to be unwound, a horizontal rod on said supports parallel to said rollers and disposed above said rollers and extending beyond said supports on opposite sides, adapted to support the cloth as it is unwound from said bolt, a pair of 45 adjustable stop members on said supports to serve as end stops for a bolt of cloth on said rollers, and means to limit the extension of said stop members.
10. An unwinder for a bolt of cloth comprising a pair of parallel supports disposed in vertical planes, a pair of spaced, horizontal rollers mounted on and between said supports, to support a bolt of cloth to be unwound, a horizontal rod on said supports parallel to said rollers and disposed above said rollers and extending beyond said supports on opposite sides, adapted to 50 support the cloth as it is unwound from said bolt, a pair of adjustable stop members on said supports to serve as end stops for a bolt of cloth on said rollers, means to limit the extension of said stop members, and means to hold said stop members in various adjusted positions.
11. An unwinder for a bolt of cloth comprising a pair of parallel supports disposed in vertical planes, a pair of spaced, horizontal rollers 55 mounted on and between said supports, to support a bolt of cloth to be unwound, a horizontal rod on said supports parallel to said rollers and disposed above said rollers and extending beyond said supports on opposite sides, adapted to support the cloth as it is unwound from said bolt, a pair of adjustable stop members on said supports to serve as end stops for a bolt of cloth on said rollers, means to limit the extension of said stop members, and means to hold said stop members in various adjusted positions.
12. An unwinder for a roll of flexible sheet material comprising a pair of spaced, parallel 60 supports, disposed in vertical planes, each support comprising an upwardly extending arm, a leg extending downwardly from said arm, a forwardly and downwardly curved portion extending from the bottom of said arm, an upwardly and forwardly curved portion extending from said first curved portion, a leg extending downwardly from said upwardly curved portion, a member interconnecting the upper ends of said upwardly and forwardly curved portions, a horizontal member interconnecting the upper ends of said arms and having extensions beyond said supports on opposite sides, said horizontal member being at a higher level than the first member, a pair of horizontal parallel rollers supported on and between said supports and disposed between said leg portions and at a lower level than said member, and extensible stop means on said supports for the ends of a roll supported on said rollers.
13. An unwinder for a roll of flexible sheet material comprising a pair of parallel vertical supports, a pair of horizontal parallel rollers supported on and between said supports and adapted to support a roll to be unwound, a horizontal rod interconnecting said supports and disposed at a higher level than said rollers and extending beyond said supports on opposite sides, to support a sheet unwound from said roll, a horizontal member interconnecting said supports and disposed at a level higher than said rollers and lower than said rod, said rollers being disposed between said member and rod, and another horizontal member interconnecting said supports and disposed between said rollers.
14. An unwinder for a roll of flexible sheet material comprising a pair of parallel vertical supports, a pair of horizontal parallel rollers supported on and between said supports and adapted to support a roll to be unwound, a horizontal rod interconnecting said supports and disposed at a higher level than said rollers and extending beyond said supports on opposite sides, to support a sheet unwound from said roll, a horizontal member interconnecting said supports and disposed at a level higher than said rollers and lower than said rod, said rollers being disposed between said member and rod, and another horizontal member interconnecting said supports and disposed between said rollers, each support being provided with a pair of legs, and said horizontal rollers being disposed between said legs, and a pair of stop members for the ends of the roll, supported on said supports, each having a horizontal portion slidably with respect to said supports, and a vertical portion adapted to engage the end of the roll.

MAXIMILIAN BRETH.
